Primary Examiner — Susan Bennett Hattan*Assistant Examiner* — Omeed Agilee(74) *Attorney, Agent, or Firm* — Acuity Law Group, PC; Michael A. Whittaker(57) **CLAIM**

The ornamental design for a diagnostic testing device, as shown and described.

DESCRIPTION

FIG. 1 is a top plan view of a diagnostic testing device showing our new design;

FIG. 2 is a front elevation view thereof;

FIG. 3 is a rear elevation view thereof;

FIG. 4 is a first side elevation view thereof;

FIG. 5 is a bottom view thereof;

FIG. 6 is a second side elevation view thereof; and,

FIG. 7 is a top and first side perspective view thereof.

The broken lines in the drawings depict portions of the diagnostic testing device that form no part of the claimed design.

1 Claim, 7 Drawing Sheets(56)
